Term of patent 3½ years

(Cl. D74—9)

FIG. 1.

FIG. 3.

FIG. 2.

FIG. 4.

FIG. 1 is a front, top and side perspective of a panel for a combined letter drop, illuminated house number, and door signal showing our new design therefor.

FIG. 2 is a front elevational view thereof.

FIG. 3 is a right side elevational view thereof.

FIG. 4 is a bottom plan view thereof.

The back of the panel is conventional.

The essential features of the design reside in the portions shown in solid lines.

The grill in FIGS. 1 and 2 is conventional and is continuous over the area shown.

We claim:

The ornamental design for a panel for a combined letter drop, illuminated house number, and door signal, as shown and described.
